UNITED STATES PATENT OFFICE.

JOSEPH VAN ACKEREN, OF PITTSBURGH, PENNSYLVANIA, ASSIGNEE TO THE HOPPERS COMPANY, OF PITTSBURGH, PENNSYLVANIA, A CORPORATION OF PENNSYLVANIA.

REGENERATIVE HEATING STRUCTURE.

Application filed July 24, 1922. Serial No. 576,985.

This invention comprehends improvements in regenerative heating apparatus generally and relates particularly to apparatus that is especially adapted for distilling carbonaceous materials. The invention has for an object the provision of a construction that is thoroughly efficient in operation and which will produce high grade coke, when employed for distilling coal, and effect a substantially complete by-product recovery by a distilling operation conducted with great conservation of heat.

Important characteristics of the invention are: the provision of a system of combustion in the flame or combustion flues of the heating walls of the distilling chambers, by which system flame or combustion is maintained concurrently in all of the flues of each heating wall, with periodic reversal in direction of flow of the heating gases and the attainment of efficient combustion and heating effects in each direction of the flow of the heating gases; the combination of this improved system of distribution with a complete reversal regenerative system for conserving the heat from the combustion flues and imparting such heat to the medium fed into the flues, the regenerative system being constructed and arranged with respect to the flues and connected therewith in such manner as to attain great efficiency in heat conservation and equality in distribution of the heating effect in the several distilling chambers of the battery; a ready adaptability for operation with an extraneously derived gas such as producer gas or blast furnace gas, for fuel, with regenerative heating of the fuel gas in some of the regenerators, without any countercurrent flow between the incoming fuel gas and the outflowing waste gas, so that waste of the fuel gas is avoided.

In addition to the general objects recited above, the invention has for further objects such other improvements and advantages in construction and operation as are found to obtain in the structures and devices herein-after described or claimed.

In the accompanying drawings forming a part of this specification and showing, for purposes of exemplification, a preferred form and manner in which the invention may be embodied and practiced, but without limiting the claimed invention to such illustrative instance or instances:

Figure 1 is a composite vertical sectional

and elevational view of a vertical retort construction embodying features above specified and constructed in accordance with the improvements of the present invention, the view being taken in the several vertical planes indicated by the lines B—B, C—C, D—D and E—E of Fig. 2;

Fig. 2 is a composite vertical sectional elevation of the retort construction taken in planes indicated by the line A—A of Fig. 1;

Fig. 3 is a composite horizontal sectional view taken in the different horizontal planes indicated by the lines F—F, G—G, H—H and J—J of Fig. 2;

Fig. 4 is a vertical sectional elevation taken in the planes indicated by the line K—K of Fig. 3, and

Fig. 5 is another vertical sectional elevation similar to Fig. 2, but illustrating a further embodiment of the invention.

The same characters of reference designate the same parts in each of the several views of the drawings.

In its present embodiment, the invention is incorporated in a vertical retort construction for producing metallurgical coke and one that is especially designed for the employment of an extraneously derived gas, such as producer gas or blast furnace gas, for fuel. For convenience, the present description will be confined to this embodiment of the invention; features of construction and operation are, however, capable of other valuable applications, for example, to apparatus generally useful in the heat treatment of materials or to constructions embodying the combination principle exemplified in my copending application for Letters Patent of the United States for Vertical retort battery, filed February 4, 1921, Serial No. 442,357, Patent 1,528,228, which discloses a vertical retort battery providing a regenerative system and gas connections such that the battery may be fired alternatively either with regeneratively preheated producer gas and regeneratively preheated air or with coke oven gas and air, the air along being regeneratively preheated; the arrangement being one in which half of the inflow regenerators may be utilized for preheating producer gas or other fuel gas that requires preheating, or all of the inflow regenerators may be utilized for preheating air when the firing is done with coke oven gas or other fuel gas that does not require preheating,

consequently the invention is not confined in its scope to the specific use and embodiment herein described as an illustrative example.

Referring to the drawings, there are illustrated views of a vertical retort battery of the by-product type, as hereinbefore mentioned. The vertical retort battery embodies in its construction a series of distilling chambers, such as the series 11 of vertical elongated retorts of coking chambers, the retorts of such series being contiguous to intermediate heating walls 12 corresponding to the respective series of retorts 11. The heating walls and the retort chambers extend to a great height as compared with their respective widths and the other cross-wise dimensions of the retort battery, and the series of retorts with their corresponding intermediate heating walls are, according to the present embodiment of the invention, respectively arranged and extend along one side of the battery assembly, whereas the regenerators extend in series along the other side of the battery assembly, as will herein-after appear. The heating walls 12 form the side walls of the respective retorts 11, as shown more particularly in Figs. 1 and 3, and the outer ends of the respective retorts as well as the heating walls are reinforced by side refractory walls designated generally by the reference character 15. Between the inner ends of the retorts 11 and their corresponding heating walls 12 is located a mediate wall structure 16 which separates said retorts and heating walls from the regenerators.

The coal to be coked is contained in coal hoppers 18 corresponding to the series 11 of retorts and supported by the superstructure 20 of the battery. These coal hoppers discharge into coal chutes 21, the lower ends of each chute communicating respectively with charging holes 23 in the upper ends of the retorts 11. The discharge of coal from the several hoppers may be controlled by the manually-operated combined gate and regulating valves 25 individual to the respective chutes 21 and interposed between said chutes and the hoppers 18 above them. The fresh coke is discharged through the openings 26 at the bottoms of the retorts 11. In order to facilitate discharge of the coke from said retorts, the side walls of the latter diverge toward the bottom and away from the central major axis of the retort, as shown more particularly in Fig. 1. Because of the great height of the retorts as compared with their width and cross-wise dimension, the retort battery is preferably employed as a continuous vertical retort. When so employed, a continuous feed of material may be maintained through the retorts 11, with continuous discharge of the finished coke from the bottoms of said retorts into discharge chutes 27 individual to

each pair of adjacent retorts, as shown in Fig. 1. In discharging through the chutes 27, the coke is guided by pivoted aprons 30 into the path of rotary dischargers 31, which insure substantially continuous movement 70 of the finished coke through the chutes 27. From the bottoms of the chutes 27, the coke may be discharged at will through manually controlled gates 32 onto inclined hoppers 33. The hoppers 33 incline downwardly, as shown in Figs. 2 and 5 toward the coke conveyor 34 and the discharge from the hoppers unto the coke conveyor 34 may be controlled by the individual pivoted gates 35 respectively operated by levers and pull rods 36. 80

The heat for coking the charges of coal in the several retorts 11 is derived from the heating walls 12 corresponding to said retorts. Each heating wall 12 is constituted of a plurality of vertical flame or combustion flues 37 that are operatively disposed into single groups in their respective heating walls. That is to say, all of the heating flues of each heating wall operate concurrently for flow in the same direction; in 90 fact, the flow is in the same direction during a reversal period throughout the entire system of flues of the battery, as will herein-after appear.

The regenerators 38 are located on that 95 side of the battery opposite from the retorts 11 and heating walls 12 and are separated from said retorts and heating walls by the mediate wall structure 16. As shown in Fig. 3, the regenerators are located in a single 100 series along one side of the battery, with the major vertical planes of the regenerators parallel with the major vertical planes of the retorts and heating walls. Operatively, the series of regenerators 38 is disposed into 105 groups R and S, each such group R and each such group S comprising four regenerators taken seriatim, and the groups R alternating with the groups S. When the several regenerators constituting the group R are 110 operating for inflow, that is to say, for delivering preheated gaseous media to the flues of the heating walls, the several regenerators of the other groups S are operating for outflow to extract heat from the flue gases discharged into the regenerators from the flues. On reversal of the battery, at the end of an 115 operating period determined by practice, the inflow regenerators become outflow regenerators and the outflow regenerators become inflow regenerators. 120

Each regenerator 38 is preferably a high narrow upright chamber containing open brickwork, commonly called checkerwork and indicated at 40 with a sole channel 41 125 underneath such checkerwork, the channels 41 forming the soles of such chambers and opening up into the checkerwork. The several regenerators are heated by the hot combustion products that are exhausted from 130

the flame or combustion flues hereinbefore mentioned and then, on reversal impart such heat to the medium that they feed into these flame flues.

5 In the operation of the battery, according to the present embodiment of the invention which employs an extraneously derived gas, such as producer gas for fuel, the several regenerators constituting the group R, when 10 in inflow operation, deliver air and fuel gas to the flame flues during the period when the latter are operating for upflow combustion; these regenerators R receive the exhaust gases from the flame flues after reversal, that is to say, during the period when the flame flues are operating for downflow combustion. On the other hand, the several regenerators constituting the group S operate for inflow of air and fuel gas to deliver 15 the same to the flues when the latter are operating for downflow combustion, and the said regenerators S operate for outflow to receive the exhaust gases from the flues during the period when the latter are operating 20 for upflow combustion. This method of operation requires the regenerators R to be connected with the lower ends of the flame flues 37 and the regenerators S to be connected with the upper ends of said flame flues. The several regenerators of each 25 group R and S are constituted of air regenerators A and gas regenerators P, when operating for inflow, and all the regenerators of each group are constituted of waste gas regenerators W when operating for outflow. However, the several regenerators R operate 30 for inflow while at the same time the several regenerators S operate for outflow and, on reversal of the flow through the flame flues, the several regenerators S are switched to the inflow function while concurrently the other regenerators R are switched to the outflow function.

In accordance with the invention, and as 45 shown in Fig. 3, the producer gas regenerators P of each group R or S are constituted of the two inside regenerators of their respective groups; whereas the air regenerators A of the groups R and S are constituted of the two outside regenerators of their respective groups. Inasmuch as the groups R alternate with the groups S and when the regenerators of the groups R are operating for inflow, several regenerators of the group S are operating for outflow, and vice versa, and because of the arrangement of the inflow fuel gas regenerators as the inside regenerators of their respective groups, only the air regenerators A of the inflow groups will be 50 adjacent to and in countercurrent relation with the waste gas regenerators W, whether the group R or S be operating for inflow. Consequently any countercurrent relation of flow between adjacent regenerators, in any 55 operation of the battery, is only between air

and waste gas regenerators and never between waste gas and fuel regenerators, with the result that there is practically no liability for the fuel gas to become short circuited and pass into the waste gas regenerators, 70 where it would be wasted. The present grouping of the inflow fuel gas regenerators to avoid this countercurrent relation with the waste gases flowing out through the waste gas regenerators is an important ad- 75 vantage because it practically eliminates any waste of fuel gas, inasmuch as the fuel gas regenerators are located remotely from any region where conditions of pressure differential must be maintained in the operation 80 of the battery. The operating conditions in regenerative heating structure practice require a pressure in the outflow regenerators somewhat less than that of the inflow regenerators and, in the construction of the present invention, only the inflow air regenerators are exposed to any losses which might accrue due to this pressure differential. In the case of the incoming air, however, any loss from short circuiting into the waste gas 90 regenerators is practically negligible in the economy of the battery operation.

The several regenerators A of the groups R lead at their upper ends into horizontal feed channels 51, the latter extending into the mediate wall structure 16 and communicating with vertical feed channels 53. These vertical feed channels 53 extend down to a level below the lower ends of the flues 37 and there communicate with horizontal feed or flow channels 54 which extend beneath the flues of alternate pairs K of adjacent heating walls. The corresponding channels 56 of the intermediate pairs L of adjacent heating walls are 105 respectively communicably connected with the respective horizontal channels 54 and through the vertical channels 53 with the regenerators A, by horizontal ducts or flow passages 55 which cross around beyond the 110 outer ends of the retorts 11 from the horizontal flow channels 54 to the horizontal flow channels 56. A distributing channel 57 is communicably connected with each channel 54 by preferably a single port 58. 115 The distributing channels 57 are communicably connected with the lower ends of the flues of the heating walls in which said channels 57 are located. In like manner, there is also provided above each channel 56 a 120 distributing channel 59 communicably connected with the channel 56 preferably by a single port 60 and also communicably connected with the flues of the heating wall in which said channel 59 is located. With this construction, each regenerator A of the several groups R is communicably connected with the lower ends of the flame flues of a pair of adjacent heating walls, and the above described duct or channel system, including 125 130

the vertical channels, the horizontal channels and the cross-around channels, provides a means whereby the lower ends of all the flame flues of the battery are communicably connected with air regenerators A of the groups R.

The several regenerators P of the groups R lead at their upper ends into horizontal feed channels 61, the latter extending into the mediate wall structure 18 and communicating with vertical feed channels 63. These vertical feed channels 63 extend down to a level below the lower ends of the flues 37 and there communicate with horizontal feed or flow channels 64 which extend beneath the flues of the alternate pairs K of adjacent heating walls. The corresponding channels 66 of the intermediate pairs L of adjacent heating walls are respectively communicably connected with the respective horizontal channels 64 and through the vertical channels 63 with the regenerators P, by horizontal ducts or flow passages 65 which cross around beyond the outer ends 25 of the retorts 11 and below the before mentioned cross-around ducts 55 from the horizontal flow channels 64 to the horizontal flow channels 66. A distributing channel 67 is communicably connected with each channel 64 by preferably a single port 68. The distributing channels 67 are communicably connected with the lower ends of the flues of the heating walls in which said channels 67 are located. In like manner, 30 there is also provided above each channel 66 a distributing channel 69 communicably connected with the channel 66 preferably by a single port 70 and also communicably connected with the flues of the heating wall 35 in which said channel 69 is located. With this construction, each regenerator P of the several groups R is communicably connected with the lower ends of the flame flues of a pair of adjacent heating walls, 40 and the described duct or channel system for the producer gas regenerators P, said system including the vertical channels, the horizontal channels and the cross-around channels, provides a means whereby the 45 lower ends of all the flame flues of the battery are communicably connected with producer gas regenerators P of the groups R.

As shown in Fig. 3, the several distributing channels 57, 59, 67 and 69 preferably extend clear through the side refractory wall 15 to permit access from the exterior of the battery into such channels for the purpose of regulating the draft through their respective ports 58, 60, 68 and 70 by means of ordinary dampers or slide bricks 71 (see Fig. 2). Normally however the open ends of the said distributing channels may be closed by suitable plugs. The said dampers 71 provide regulation for the flow through the flame flues 37 in both upflow

and downflow combustion, inasmuch as the flow must pass through the ports 58, 60, 68 and 70, whether the combustion be up or down in the flame flues. In the form of the invention illustrated in Figs 1 to 4 inclusive, this situation is advantageously employed to simplify somewhat the flow passage construction at the tops of the flues, as will presently appear.

As hereinbefore stated, the several regenerators of the group S are for the purpose of supplying preheated gaseous media to the tops of the flame flues 37 of the several heating walls 12, during the reversal periods when downflow combustion is maintained in said flame flues. The several regenerators A of the groups S lead at their upper ends into horizontal feed channels 72, the latter extending through the mediate wall structure 16 and communicating directly with horizontal distributing channels 73 which extend above the tops of the flues of the intermediate pairs L of adjacent heating walls and are directly communicably connected with said flues by ports 74. The corresponding channels 75 of the alternate pairs K of adjacent heating walls are respectively communicably connected with the tops of the flues by ports 76 and are also respectively communicably connected with the horizontal channels 73 and through the channels 72 with the regenerators A, by horizontal ducts or flow passages 77 which cross around beyond the outer ends of the retorts 11 from the horizontal channels 73 to the horizontal channels 75. With this construction, each regenerator A of the several groups S is communicably connected with the upper ends of the flame flues of a pair of adjacent heating walls, 105 and the above described duct or channel system, including the horizontal channels and the cross-around channels, provides a means whereby the upper ends of all the flame flues of the battery are communicably connected with air regenerators A of the groups S.

In like manner, the several regenerators P of the groups S lead at their upper ends into horizontal feed channels 78, the latter extending through the mediate wall structure 16 and communicating directly with horizontal distributing channels 79 which extend above the tops of the flues of the intermediate pairs L of adjacent heating walls 120 and are directly communicably connected with said flues by ports 80. The corresponding channels 81 of the alternate pairs K of adjacent heating walls are respectively communicably connected with the tops of the flues by ports 82 and are also respectively communicably connected with the horizontal channels 79 and through the channels 78 with the regenerators P, by horizontal ducts or flow passages 83 which cross 125

around beyond the outer ends of the retorts 11 from the horizontal channels 79 to the horizontal channels 81. With this construction, each regenerator P of the several groups S is communicably connected with the upper ends of the flame flues of a pair of adjacent heating walls, and the above described duct or channel system, including the horizontal channels and the cross-around channels, provides a means whereby the upper ends of all the flame flues of the battery are communicably connected with producer gas regenerators P of the groups S.

As shown in Fig. 3, the several upper horizontal channels 73, 75, 79 and 81 may extend clear through the side refractory wall 15, for the purpose of permitting access from the exterior of the battery to said channels. The draft through the upper ends of the individual flame flues communicably connected with said channels may be regulated by ordinary dampers or slide bricks 84 (see Fig. 4) for individually controlling the flow through the ports at the tops of the flues. Normally the outer ends of said channels 73, 75, 79 and 81 are closed by suitable plugs.

Extending longitudinally of the battery is a waste gas tunnel or stack flue 85 (Figs. 2 and 5), the waste gas tunnel 85 serving for either of the groups R or S of regenerators, when operating as waste gas regenerators for the outflow of the waste gases. The said waste gas tunnel 85 leads to the usual waste gas stack. Flow boxes 86 connect the sole channels of the several regenerators of both groups R and S individually with the waste gas tunnel 85. The flow boxes 86 are provided with valves 87 for controlling the flow between the individual regenerators and the waste gas tunnel. The valves 87 of all the generators of the group S are open, while concurrently the corresponding valves of all of the regenerators of the group R are closed. On reversal of the battery, the valves 87 of the groups R of regenerators are open and the corresponding valves of the group S are closed. Each regenerator A of both groups R and S is provided with a lid 88 (Fig. 1) which when open permits air to flow into its flow box and thence into the regenerator. The series of air lids 88 of the regenerators of the groups R and S are opened in alternation, whereby all the regenerators A of the group R operate concurrently for inflow of air during one reversal period and thereafter, during the next reversal period, the regenerators A of the group S operate for inflow of air, while the regenerators A of the group R are operating for outflow of the waste gases.

The fuel gas main 89 extends longitudinally of the battery and is provided with individual valve connections 90 to the several regenerators P of both groups R and S. In

the operation of the battery, the valve connections of the regenerators P of the group R are operated in unison to permit the flow of fuel gas into said regenerators from the main 89, while the valve connections 90 of the regenerators P of the group S are closed to shut off the supply of fuel gas. On reversal of the battery, the valve connections 90 are operated to permit the supply of gas into the regenerators P of the group S and concurrently to cut off the supply of gas from the regenerators P of the group R.

The several flame flues 37 of the battery may be conveniently reached by access flues 91 located in the top structure of the battery and positioned above the ports at the upper ends of the respective flues. Normally these access flues 91 are closed by the usual removable covers (not shown).

In the form of the invention shown in Fig. 5 the several regenerators 38 are extended to a level below the discharge outlets of the coke chutes, thereby increasing the regenerative capacity of the battery. A further departure in this form of the invention is made with respect to the arrangement of the distributing channels above the flues. Instead of the tops of the regenerators A and P of both groups R and S directly communicating with the distributing channels 73, 75, 79 and 81 and cross-around ducts 77 and 83, the connection between such channels is made by the intermediary of flow channels 92 analogous to the hereinbefore described flow channels 54, 56, 64 and 66 at the bottoms of the heating walls, said channels 92 leading preferably by single ports 93 into their respective distributing channels and being also provided with inspection holes 94 leading to the outside of the battery. The cross-around ducts connect channels 92 of adjacent heating walls, said channels 92 serving as the connecting means between the cross-around ducts and the distributing channels 73, 75, 79 and 81. This construction enables the downflow combustion to be regulated through a single port 93 for each distributing channel and independently of the upflow combustion. The regulation of the flow through the ports 93 may be accomplished by ordinary slide bricks or dampers 95. The vertical ducts 91 below the channels 92 may be closed, when not in use, by covers 96 located in the bottom of the channels 92. Normally the inspection holes 94 of said channels 92 are closed by suitable plugs.

The operation of the retort battery, assuming that a relatively lean or dilute gas, such as ordinary producer gas is employed as the fuel in the flues of the heating walls, is as follows: if it be assumed that the several regenerators comprising the group R be operating for inflow and the flues throughout the battery be operating for upflow com-

bustion, it follows that during this period the regenerators P of the group R are employed for preheating the fuel gas which is subsequently introduced into the flues. The 5 regenerators A of the group R are employed for preheating the air to support the combustion of the gas in the flues. Concurrently, all of the regenerators of the group S operate for outflow, or as waste gas regen- 10 erators W. The air and fuel gas passes upwardly through the regenerators A and P of the group R thence downwardly through the vertical channels 53 and 63, thence into the horizontal channels 54 and 64 (see sec- 15 tion JJ, Fig. 3) and through the cross-around ducts 55 and 65 into the horizontal channels 56 and 66. From said horizontal channels 54, 56, 64 and 66 the air and fuel gas passes into the distributing channels 57, 20 59, 67 and 69 through the ports 58, 60, 68 and 70. These distributing channels deliver the air and fuel gas to the bottoms of the flues 37. Passing upwardly through the flues 37 the air and fuel gas burn. At the 25 tops of the flues the waste gases pass out through the ports 74, 76, 80 and 82 into the channels (see section FF, Fig. 3) 73, 75, 79 and 81 and thence through the connecting channels 72 and 78 into the regenerators of 30 the group S. The cross-around ducts 77 and 83 respectively deliver the flow from the channels 75 into the channels 73 and from the channels 81 into the channels 79. Pass- 35 ing downwardly through the regenerators S the waste gases flow through the open flow boxes 86 of such regenerators into the waste gas tunnel 62. On reversal of the battery, the flow is exactly reversed through the flow passages just described. The regenerators 35 A and P of the group S deliver to the tops of the flues the air and fuel gas and the waste gases from said flues exhaust from the bottom thereof into the tops of the regenerators of the group R. Flowing downwardly 40 through said regenerators, the waste gases ultimately pass through their open flow boxes into the waste gas tunnel.

The by-products and distillate gases from the several retorts or coking chambers 11 pass out of the tops of said retorts through ascension pipes 97 individual to the respective retorts 11. These ascension pipes carry the distillate and by-product to a common collecting main 98, through which the distillate and by-products may pass to the by-product recovery apparatus.

The invention as hereinabove set forth may be variously embodied within the scope of the claims hereinafter made.

55 I claim:

1. In a vertical retort battery, in combination: a plurality of high narrow retort chambers, each receiving through its top the charge to be coked and discharging through 60 its bottom the coked charge; heating walls

contiguous to such retort chambers and respectively comprising combustion flues alternately operable in unison for either upflow or downflow combustion; upper pairs of feed channels respectively communicably connected with the tops of the flues; lower pairs of feed channels respectively communicably connected with the bottoms of the flues; the respective feed channels of alternate heating walls being communicably connected with the corresponding feed channels of the intermediate heating walls by flow ducts crossing around the outer ends of the retort chambers; alternate and intermediate groups of high narrow regenerators, the 70 regenerators of one group being communicably connected with alternate pairs of upper feed channels, and the regenerators of the other group being communicably connected with the alternate pairs of lower feed channels, each group of regenerators when operating for inflow comprising both fuel gas and air regenerators, with the fuel gas regenerators disposed in the inside of the group and the air regenerators at the 80 outside, whereby countercurrent flow between inflow fuel gas regenerators and outflow waste gas regenerators, in regenerators alongside each other, is prevented; substantially as specified. 95

2. In a vertical retort battery, in combination: a plurality of retort chambers; heating walls contiguous to such retort chambers and respectively comprising combustion flues alternately operable in unison for either upflow or downflow combustion; upper pairs of feed channels respectively communicably connected with the tops of the flues; lower pairs of feed channels respectively communicably connected with the bottoms of the flues; the respective feed channels of alternate heating walls being communicably connected with the corresponding feed channels of the intermediate heating walls by flow ducts crossing around the outer ends of the retort chambers; alternate and intermediate groups of regenerators, the regenerators of one group being communicably connected with alternate pairs of upper feed channels, and the regenerators of the other group being communicably connected with the alternate pairs of lower feed channels, each group of regenerators when operating for inflow comprising both fuel gas and air regenerators, with the fuel gas regenerators disposed in the inside of the group and the air regenerators at the outside, whereby countercurrent flow between inflow fuel gas regenerators and outflow waste gas regenerators, in regenerators alongside each other, is prevented; substantially as specified. 100

3. In a vertical retort battery, in combination: a plurality of retort chambers; heating walls contiguous to such retort chambers and respectively comprising combus- 105

- tion flues alternately operable in unison for either upflow or downflow combustion; upper feed channels respectively communicably connected with the tops of the flues; 5 lower feed channels respectively communicably connected with the bottoms of the flues; the respective feed channels of alternate heating walls being communicably connected with the corresponding feed channels 10 of the intermediate heating walls by flow ducts crossing around the outer ends of the retort chambers; alternate and intermediate groups of regenerators, the regenerators of one group being communicably connected with alternate upper feed channels, and the regenerators of the other group being communicably connected with the alternate lower feed channels, each group of regenerators when operating for inflow comprising both fuel gas and air regenerators, with the fuel gas regenerators disposed in the inside of the group and the air regenerators at the outside, whereby countercurrent flow between inflow fuel gas regenerators 15 and outflow waste gas regenerators, in regenerators alongside each other, is prevented; substantially as specified.
4. In a vertical retort, in combination; a plurality of retort chambers; heating walls contiguous to such retort chambers and respectively comprising combustion flues; upper feed channels respectively communicably connected with the tops of the flues; lower feed channels respectively communicably connected with the bottoms of the flues; the respective feed channels of alternate heating walls being communicably connected with the corresponding feed channels of the intermediate heating walls by flow 20 ducts crossing around the outer ends of the retort chambers; and regenerators some of which are communicably connected with upper feed channels, and other of which are communicably connected with the lower feed channels; substantially as specified.
5. A vertical retort battery having retort chambers and flued heating walls contiguous to said retort chambers; combined with regenerators communicably connected with the flues of the heating walls and disposed in inflow groups alternating in position side by side with outflow groups, each group of regenerators when operating for inflow comprising both fuel gas and air regenerators, with the fuel gas regenerators disposed in the inside of such groups and the air regenerators at the outside, whereby countercurrent flow between inflow fuel gas regenerators and outflow waste gas regenerators, in regenerators alongside each other, is prevented; substantially as specified.
6. A regeneratively heated vertical retort furnace with the regenerators, which comprise regenerators operable for preheating fuel gas, disposed side by side in a single row, alongside a row of retorts and flued heating walls for the retorts, said regenerators being communicably connected at their tops with the flues of said flued heating walls, characterized by the regenerators which at any time have fuel gas flowing therein being always separated on both sides from the regenerators operating in counterflow, by intervening regenerators in which the flow is in the same direction as in the said fuel gas regenerators.
7. A furnace as claimed in claim 6, characterized by the arrangement that groups of four regenerators operating for inflow alternate with the groups of four regenerators operating for outflow, and the fuel gas supplying regenerators of a group operating for inflow are disposed at the inside of the group and the air supplying regenerators of the group disposed at the outside.
8. A vertical retort battery having retort chambers and flued heating walls contiguous to said retort chambers; combined with regenerators communicably connected with the flues of the heating walls and arranged alongside each other and disposed in a series of side-by-side groups adapted respectively to serve alternately for inflow of both fuel gas and air and outflow of waste-gas, and the regenerators for inflow of fuel gas being separated from all the regenerators for concurrent outflow of waste-gas by intervening regenerators for air.
9. A vertical retort battery having vertical retort chambers and heating walls between and contiguous to said retort chambers, each of said heating walls comprising vertical combustion flues operable in unison for upflow and downflow combustion in alternation, combined with regenerators arranged side by side in a row alongside said retort chambers and heating walls and disposed in two series of groups of at least three regenerators each, the regenerators of one of said series being communicably connected with the flues at the tops thereof and the regenerators of the other series of groups with the flues at the bottoms thereof, the groups of one of said series alternating in position with the groups of the other of said series, each of the groups of regenerators comprising two regenerators for inflow of air respectively disposed on the outside of the group and at least one regenerator for inflow of fuel gas disposed between the air regenerators, whereby countercurrent flow between fuel gas and waste gas in regenerators alongside each other is prevented.

In testimony whereof I have hereunto set my hand.

JOSEPH VAN ACKEREN.
